UNITED STATES PATENT OFFICE.

MAGNUS SWENSON, OF CHICAGO, ILLINOIS, ASSIGNOR TO THE AMERICAN COTTON COMPANY, OF NEW JERSEY.

BAT-FORMING MECHANISM.

SPECIFICATION forming part of Letters Patent No. 621,952, dated March 28, 1899.

Application filed February 18, 1898. Serial No. 670,807. (No model.)

To all whom it may concern:

Be it known that I, MAGNUS SWENSON, a citizen of the United States, and a resident of Chicago, in the county of Cook and State of Illinois, have invented a new and useful Mechanism for Forming a Bat of Cotton or other Similar Fibrous Substance, of which the following is a specification.

This invention relates to an improved mechanism for forming a bat of cotton or other similar substance.

A bat-forming mechanism employing my invention is particularly adapted for use in connection with a rotary cotton-press of the type in which a bat of cotton is wound, under pressure, into a cylindrical bale. Heretofore the common practice has been to form the bale from the bat as it comes from the condenser; but this is objectionable for the reason that the construction and operation of the condenser limit the thickness of the bat formed thereby, thus forming a bat which is too thin and weak to be unwound after having been formed into a bale.

A primary object of my invention is to provide a bat-forming mechanism particularly designed for use in connection with a rotary cotton-press which will form a bat of such thickness and strength that after having been wound into a bale it may be again unwound.

In the preferred form thereof now known to me a bat-forming mechanism embodying my invention comprises an inclosed hopper, two opposed sides of which are formed by belts or endless aprons supported upon pulleys mounted so as to be freely revoluble in such position that the adjacent sides of said belts or aprons will converge downwardly; means to actuate said belts or aprons so that the adjacent sides thereof will travel in the direction of their convergence, and means to pick or open the cotton as it is delivered to said hopper, said means comprising a pair of small driven feed-rolls, between which the cotton is delivered into the hopper, and a picker-cylinder mounted in such position that the ends of the teeth thereof will pass in close proximity to the surfaces of said feed-rolls and which is driven at a relatively high surface speed as compared with said feed-rolls.

The invention also consists of the various

features, combinations of features, and details of construction hereinafter described and then pointed out in the claims.

In the accompanying drawings a bat-forming mechanism embodying my invention is fully illustrated.

Figure 1 is a front view of a bat-forming mechanism embodying my invention, the front belt or apron being indicated in diagram 60 only. Fig. 2 is a vertical sectional view thereof on the line 2 2 of Fig. 1, and Figs. 3 and 4 show in detail the construction of the belts of the hopper or receptacle.

Referring to the drawings, A A' are belts 65 movably supported in such relative positions that the adjacent sides thereof will converge downwardly and the lower ends thereof will be separated by a space of desired width.

The belts A A' may be of any desired or 70 approved construction. As shown they consist of wooden slats a , covered with cloth a' , preferably duck, canvas, or the like, said slats being secured to the links of chain belts a^2 . Said belts A A' are supported upon sprocket-wheels a^3 , to which the chain belts a^2 are adjusted, and said sprocket-wheels a^3 are secured to shafts a^4 , revolubly mounted in proper position.

The belts A A' are driven in such a manner that the adjacent sides thereof will travel downward toward their point of convergence, as indicated by the arrows. As shown, said belts are driven by means of a belt A^2 , adjusted to a pulley a^5 , secured to one of the 85 lower shafts a^4 , and spur-gears a^6 , one secured to each of said lower shafts a^4 , so as to engage with each other.

The sides of the space between the belts A A' are closed by stationary walls A^3 , which, 90 together with said belts, form a hopper or receptacle inclosed on its four lateral sides and having a discharge-opening a^7 at the lower end thereof. For purposes of convenient reference said hopper or receptacle will be hereinafter designated as a whole by the reference-letter A⁴.

As shown, the shafts a^4 , which support or drive the belts A A', are supported upon the frame of the end walls A^3 .

Revolubly mounted at the upper end of the hopper or receptacle A⁴ are a picker-cyl-

inder B and a pair of feed-rolls B'. The picker-cylinder B consists of a solid hub or body portion B² and a plurality of picker-teeth b, secured therein. The feed-rolls B' are preferably made as small as practicable, a desirable size therefor being about three inches in diameter. The picker-cylinder B is preferably made much larger than the feed-rolls B', a desirable size therefor being about eighteen inches (18) in diameter, and said picker-cylinder is so located relatively to said feed-rolls that the ends of the picker-teeth b will pass in close proximity to the surface of said feed-rolls.

15   Rotary movement in the directions indicated by the arrows is imparted to the picker-cylinder B and to the feed-rolls B'. The surface speed of the feed-rolls is usually about the same as that of a condenser, while the picker-cylinder is driven at a much higher rate, a desirable speed being about six hundred and fifty revolutions per minute.

As shown, the bearings for the shafts of the picker-cylinder B and of the feed-rolls B' are formed in a suitable frame B³, supported upon the frame of the walls A³ of the hopper, said frame B³ being preferably made of cast-iron.

In order to prevent loose cotton from being carried out of the top of the hopper or receptacle, said hopper or receptacle is provided with a suitable cover which extends between the side walls A³ thereof above the picker-cylinder B. As shown, the cover consists of a closed section B³, supported below the top of the picker-cylinder B, and of an open or screen portion B⁴, which is curved or bent upwardly over said picker-cylinder B and extends into close proximity to the upper feed-roll B'. Preferably, also, the position of the screen-section B⁴ is such that the ends of the picker-teeth b will pass in close proximity thereto. Said picker-teeth will thus operate to keep said screen-section clean, so as to allow air to escape therethrough. A considerable quantity of dust will pass through said screen B⁴, which is thus eliminated from the cotton.

The operation of my improved bat-forming mechanism is as follows: The operative parts thereof being first set in motion, cotton or other fiber is delivered between the feed-rolls B' to the picker-cylinder B, which operates, in combination with the said feed-rolls B', to pick the cotton into a loose fluffy mass, which is discharged into the hopper A⁴ beneath said picker-cylinder B and is formed into a coherent bat of any desired thickness and discharged through the opening a⁷ by the operation of the belts A A'. The thickness and strength of the bat depend upon the speed of the belts and the amount of cotton delivered to the hopper A⁴ in a given time—that is to say, if the speed of the belts is relatively slow compared to the speed of the condenser-cylinders the bat produced by and fed from the belts will be formed more slowly than the bat

formed by the condenser-cylinders, and since it of course contains the same bulk of cotton it is necessarily thicker, and consequently stronger. In this way I am enabled to operate the condenser-cylinder at a relatively high speed to accommodate a large number of gins and to operate the belts at relatively slow speed, so as to produce a very thick uniform and cohesive bat.

In the drawings I have shown, in connection with my improved bat-forming mechanism, the diagram of a cotton-condenser, the type of condenser shown being that known as a "double-cylinder" condenser. The circles C indicate the cylinders of the condenser, and C' are doffer-rolls adapted to strip the bat of cotton from said condenser-cylinders, whence it passes to the feed-rolls B'. In the drawings I have also shown so much of a rotary cotton-press as will illustrate the application of my improved bat-forming mechanism thereto and which I will now describe.

D is a portion of the cotton-press frame. 90 D' represents the stationary compression-cylinder, D² the movable compression-cylinder, and D³ a bale of cotton in process of formation between said cylinders. The means for rotating the compression-cylinders and the means to generate the pressure on the bale are old and well known in the art and are not shown, as they are not necessary to the understanding of my present invention.

Supported above the stationary compression-cylinder D' is what may be termed a "feed-roll" D⁴. As shown, the bearings for said roll D⁴ are formed in blocks d, fitted to guide-slots formed in brackets D⁵, secured to the press-frame D. Threaded through the ends of the brackets D⁵ are screws d', which bear upon caps D⁶, between which and the tops of the bearing-blocks d are inserted rubber cushions d², which will obviously allow the roll D⁴ to yield slightly away from the compression-roll D'.

The bat of cotton from my improved bat-former is discharged through the opening a⁷ upon a guide or chute D⁷, which conducts it between the compression-roll D' and the feed-roll D⁴, subjecting it to a strong compression, which operates to felt the bat and also to force the air out of it. The bat then passes around the core-roll of the press, and the process of forming the bale proceeds in the usual manner.

If for any reason deemed desirable, my invention contemplates substituting for one of the belts A A' a stationary wall. In case this construction is adopted said stationary wall will preferably be made substantially vertical and will be made very smooth.

I do not claim to be the inventor of a hopper or receptacle comprising two opposed sides which converge together, one or both of said sides formed by a movably-supported belt, for the reason that such a device is the invention of William E. Anderson, application filed July 12, 1895, Serial No. 555,733; but I

claim the same only when used in connection or in combination with means for allowing the discharge of the air from the cotton forced through the gin-flue, whereby the cotton will be deposited in said hopper in a light fluffy state.

What I claim is—

1. In a device for making a cotton-bat, the combination with the gin-flue through which the cotton is forced by air-currents and means for allowing the discharge of the air therefrom and for depositing the cotton in a light fluffy state, of a hopper or receptacle into which the fiber is delivered in such state, said hopper comprising two opposed sides which converge together, one or both of said sides being formed by a movably-supported belt, there being a discharge-opening between the adjacent ends of the converging sides of said hopper, and means for slowly driving the movable side or sides of the hopper, whereby the cotton accumulated therein will be forced toward and out of the discharge-opening and compressed gradually so as to leave the discharge-opening as a thick, homogeneous and cohesive bat, substantially as set forth.

2. In a device for making a cotton-bat, the combination with a condenser for forming a preliminary bat, of a hopper or receptacle comprising two opposed sides which converge together, one or both of said sides being formed by a movably-supported belt, there being a discharge-opening between the adjacent ends of the converging sides of said hopper, means for picking and opening the bat formed by the condenser and for depositing the cotton into the hopper in a light fluffy state, and means for driving the movable side or sides of the hopper at a slower speed than that of the condenser, whereby the cotton accumulated in the hopper will be forced toward and out of the discharge-opening and compressed gradually so as to leave the discharge-opening as a thick, homogeneous and cohesive bat, substantially as set forth.

3. In a device for making a cotton-bat, the combination with a condenser for forming a preliminary bat, of a hopper or receptacle comprising two opposed sides which converge together, one or both of said sides being formed by a movably-supported belt, there being a discharge-opening between the adjacent ends of the converging sides of said hopper, a pair of feed-rolls between which the bat formed by the condenser is passed, a picker-cylinder having a plurality of picker-teeth arranged to rotate adjacent to said feed-rolls and to pick and open the bat formed by the condenser, and deposit the cotton into the hopper in a light fluffy state, and means for driving the movable side or sides of the hopper at a slower speed than that of the condenser, whereby the cotton accumulated in the hopper will be forced toward and out of the discharge-opening and compressed gradually so as to leave the discharge-opening as a thick, homogeneous and cohesive bat, substantially as set forth.

4. In a device for making a cotton-bat, the combination of a hopper or receptacle comprising two opposed sides converging downwardly, one or both of said sides being formed by a movably-supported belt, there being a discharge-opening between the lower ends of the converging sides of the hopper, and the top of said hopper being closed to the escape of cotton, means for driving the movable side or sides of the hopper, and means for supplying cotton to said hopper in a loose and fluffy state, whereby the cotton accumulated therein will be forced downward toward and out of the discharge-opening and compressed gradually so as to leave the discharge-opening as a thick, homogeneous and cohesive bat, substantially as set forth.

5. In a device for making a cotton-bat, the combination of a hopper or receptacle comprising two opposed sides which converge downwardly, one or both of said sides being formed by a movably-supported belt, there being a discharge-opening between the lower ends of the converging sides of said hopper, means for driving the movable side or sides of said hopper, means for supplying the cotton to the hopper by air-currents, and a perforate or screen section in the top of the hopper for the escape of the air, whereby the cotton will accumulate and settle in said hopper as a light mass, and be forced toward and out of the discharge-opening and compressed gradually so as to leave the discharge-opening as a thick, homogeneous and cohesive bat, substantially as set forth.

6. In a bat-forming mechanism, the combination with a condenser, of a hopper or receptacle into which the cotton or other fibrous substance is delivered from the condenser, said hopper comprising two opposed sides formed by movably-supported belts, which converge downward, a discharge-opening between the lower ends of the adjacent sides of said belts, means to drive said belts so that the adjacent sides thereof will move downward toward their line of convergence, and means to pick or open the cotton delivered to said hopper or receptacle, said means comprising feed-rolls and a picker-cylinder mounted within and at the upper end of the hopper or receptacle, said picker-cylinder consisting of a rigid body portion and a plurality of picker-teeth secured therein, and said feed-rolls and picker-cylinder being supported in such relative positions that the ends of the picker-teeth will pass in close proximity to the surfaces of said feed-rolls, and means to actuate said feed-rolls and picker-cylinder, the top of said hopper being closed by a cover which comprises a perforated or screen section which is bent or curved over the picker-cylinder in such position that the ends of the picker-teeth will pass in close proximity thereto, substantially as set forth.

7. In a mechanism for making cylindrical cotton-bales, the combination with a press for winding a bat convolutionally under pres-

- sure, of means for making a cotton-bat, comprising a hopper or receptacle into which the fiber is delivered by air-currents in a light fluffy state, said hopper comprising two opposed sides which converge together, one or both of said sides being formed by a movably-supported belt, a discharge-opening between the adjacent ends of the converging sides of said hopper, means to allow for the escape of the air, whereby the cotton will be free to accumulate and settle in said hopper as a light mass, and means for slowly driving the movable side or sides of the hopper, whereby the cotton accumulated therein will be forced toward and out of the discharge-opening and compressed gradually so as to leave the discharge-opening and enter the cotton-press as a thick, homogeneous and cohesive bat, substantially as set forth.
20. In mechanism for making cylindrical cotton-bales, the combination with a press for winding a bat convolutionally under pressure, of a device for making a cotton-bat, comprising a condenser for forming a preliminary bat, a hopper or receptacle comprising two opposed sides which converge together, one or both of said sides being formed by a movably-supported belt, a discharge-opening between the adjacent ends of the converging sides of said hopper, means for picking and opening the bat formed by the condenser and for depositing the cotton into the hopper in a light fluffy state, and means for driving the movable side or sides of the hopper at a slower speed than that of the condenser, whereby the cotton accumulated in the hopper will be forced toward and out of the discharge-opening and compressed gradually so as to leave the discharge-opening and enter the cotton-press as a thick, homogeneous and cohesive bat, substantially as set forth.
35. The combination with a cotton-press, of the type adapted to form a bale from cotton delivered thereto in the form of a continuous bat, of means to form a coherent bat of desired thickness, said means consisting of a hopper or receptacle into which loose or fluffy cotton or the like is delivered, said hopper comprising two opposed sides formed by movably-supported belts, which converge downward, an opening between the lower ends of the adjacent sides of said belts and means to drive said belts so that the adjacent sides thereof will move downward toward said discharge-opening, and a chute or guide to conduct the bat of cotton from said discharge-opening to the press, substantially as set forth.
50. The combination with a cotton-press of

the type adapted to form a bale from cotton or the like delivered thereto in the form of a continuous bat, of means to form a coherent bat of desired thickness, said means consisting of a hopper or receptacle into which cotton or the like is delivered, said hopper comprising two opposed sides which converge downwardly, one or both of said sides being formed by a movably-supported belt, a discharge-opening between the lower ends of the converging sides of said hopper, means to impart movement to said belt or belts downward toward the discharge-opening, and means to pick or open the cotton or other fiber delivered to said hopper, and a chute or guide to conduct the bat from said discharge-opening to the press, substantially as set forth.

11. The combination with a cotton-press, of the type in which a bat of cotton is wound under pressure into a cylindrical bale, of means to form a coherent bat of desired thickness, said means consisting of a hopper or receptacle into which loose or fluffy cotton or the like is delivered, said hopper comprising two opposed sides formed by movably-supported belts which converge downward, a discharge-opening between the lower ends of the converging sides of said hopper, means to impart movement to said belts downward toward the discharge-opening, and means to pick or open the cotton or other fiber delivered to said hopper, and a chute or guide to conduct the bat from said discharge-opening to the press, substantially as set forth.

12. The combination of a cotton-press of the type comprising a compression-cylinder supported in stationary bearings, and a core-roll and a compression-cylinder supported in sliding bearings, of means to form a coherent bat of cotton of desired thickness, said means consisting of a hopper or receptacle into which loose or fluffy cotton or the like is delivered, said hopper comprising two opposed sides formed by movably-supported belts which converge downward, a discharge-opening between the lower ends of the converging sides of said hopper, means to impart movement to said belts downward toward the discharge-opening, and means to pick or open the cotton or other fiber delivered to said hopper, and a chute or guide to conduct the bat from said discharge-opening to the press, substantially as set forth.

This specification signed and witnessed this 15th day of February, 1898.

MAGNUS SWENSON.
